[57] CLAIM

The ornamental design for an optical sight mount, substantially as shown and described.

DESCRIPTION

FIG. 1 is a perspective view of the optical sight mount with a hand gun and optical sight shown in phantom lines for illustrative purposes only;

FIG. 2 is a front elevational view of the optical sight mount;

FIG. 3 is a left side view thereof;

FIG. 4 is a rear elevational view of the optical sight mount;

FIG. 5 is a right side view thereof;

FIG. 6 is a top plan view thereof;

FIG. 7 is a bottom plan view thereof; and

FIG. 8 is a perspective view of the optical sight mount.
